(57) CLAIM

The ornamental design of an absorbent, stretchable and washable cover pant for a diaper as shown and described.

DESCRIPTION

FIG. 1 is a front view of an absorbent, stretchable and washable cover pant for a diaper showing my new design.

FIG. 2 is a rear view thereof;

FIG. 3 is a right side view thereof;

FIG. 4 is a left side view thereof;

FIG. 5 is a top view thereof; and,

FIG. 6 is a bottom view thereof.

The broken lines shown in the drawings illustrate stitching, which forms part of the claimed design.
